1,263,664.

T. E. HANADA.
GAME CARDS.
APPLICATION FILED MAY 15, 1917.

Patented Apr. 23, 1918.

Fig. 1

Fig. 3

Fig. 2.

Fig. 4

Witness
G. C. Walling
H. M. Test

By

T. E. Hanada

Attorney

Inventor

T. E. Hanada

UNITED STATES PATENT OFFICE.

TOICHI E. HANADA, OF NEW YORK, N. Y.

GAME-CARDS.

1,263,664.

Specification of Letters Patent. Patented Apr. 23, 1918.

Application filed May 15, 1917. Serial No. 168,810.

To all whom it may concern:

Be it known that I, TOICHI E. HANADA, a citizen of the United States, residing at New York city, in the county of New York, State of New York, have invented certain new and useful Improvements in Game-Cards; and I do hereby declare the following to be a full, clear, and exact description of the invention, such as will enable others skilled in the art 10 to which it appertains to make and use the same.

This invention relates to improvements in games and particularly to card games.

One object of the present invention is to 15 provide a card game which will be amusing as well as instructive.

Another object is to provide a game which will familiarize the players with the sayings of great men, the writings of great authors 20 and their nationality, as well as other matters of educational value.

Other objects and advantages will be apparent from the following description when taken in connection with the accompanying 25 drawing.

In the drawing:

Figure 1 is a view of one side of a "teller" card.

Fig. 2 is a view of one side of a "finder" 30 card.

Fig. 3 is a view of the other side of the "finder" card.

Fig. 4 is a view of the face of another "finder" card.

The game, as illustrated in the accompanying drawing, includes one-hundred and twenty cards. One set is termed the "tellers," and in the drawing is shown in Fig. 1. 35

The faces of these cards are printed with poems, sayings, proverbs, or the like, and also with the names of the authors, together with initial letters representing the first letters of the names of the countries from which the authors come. In the present case 40

the "teller" cards include two kinds, those marked with "A" for the American authors and "E" for the English authors, there being thirty of each. The reverse side of each of the "teller" cards is blank.

There are two sets of the "finder" cards, each containing thirty cards, the whole to be equally divided between two players. On the face of each "finder" card there is the same matter that is found on the different 55 "teller" cards which correspond thereto. The reverse sides of these "finder" cards contain the pictures of the authors of the matter on the faces, together with the initials of the nationalities.

On the faces of the other type of "finder" 60 cards there are printed poems, sayings, proverbs, or the like, corresponding to the like matter found on the "teller" cards. On the reverse sides of these cards are found the pictures and the initial letters representing 65 the nationalities of the authors. In the first instance, the nationality is represented by the initial letter "A" for the American author, while in the second instance the initial letter "E" shows that the authors are of 70 English birth.

In playing the game, the "teller" cards are separated from the pack and taken by the dealer. The remainder of the cards are separated from the pack, the "A's" and "B's" 75 together, and like the "teller" cards, held by the dealer. Then each player must select either the "A" cards or the "B" cards as his own, before the game.

The two players sit opposite each other, 80 at the table, while the dealer sits between at one of the other sides of the table. The cards of the players are then laid on the table with their legend sides uppermost and the pictures of the authors down. The 85 dealer then reads the matter on the "teller" cards, one at a time, and the players are to glance over all of the cards before him and those before his opponent. It will, of course, be understood that the cards of the players 90 are laid on the table in such manner that they may be readily read by both players. The player who first finds the card on the table which contains the matter read by the dealer, places his finger on that card and 95 calls "right" to indicate that he has found the card and that the dealer should read the next one. The card touched by the player is taken from the table and retained until the end of the game.

When the player finds all of his own "finder" cards without missing one, every one of his opponent's "finder" cards which he found will count so many points for the player, but if he misses one of his own 105 "finder" cards to his opponent, his opponent's "finder" cards which he found will count according to the numbers on the "teller" cards. Thus there is produced a game which is amusing and instructive, and 110 which will train the persons to be quick of hearing, sight, and action.

What is claimed is:

1. A set of game cards including a plurality of sets each having legends on one side and a picture of the author of the legend on the other side together with the initial representing his nationality, and a set having one side blank and the other side inscribed with legends corresponding to those of the other sets in addition to numbers and symbols of the nationalities of the authors of the legends, and the names thereof.
- 10 2. A set of game cards including a set of "teller" cards having one side blank and the other side inscribed with a poem or the like, the name of the author, the nationality of the author, and a number representing points of the game, and two sets of cards each having on one side a poem or the like corresponding to one of the "teller" cards, the other side of each of the cards of said second-named sets containing the picture of the author of the poem or the like, an initial of the nationality of the author, said second-named sets being designated "finder" cards.

20

25

In testimony whereof, I affix my signature in the presence of two witnesses.

TOICHI E. HANADA.

Witnesses:

PETER B. REILLY,
JOSEPH SARTORI.

Copies of this patent may be obtained for five cents each, by addressing the "Commissioner of Patents, Washington, D. C."